MULTIPLE POSITION SWITCH

Theodore J. Obszarny, Chicago, Ill., assignor to
 Guardian Electric Manufacturing Co., Chicago,
 Ill., a corporation of Illinois

Application August 9, 1953, Serial No. 303,567

8 Claims. (Cl. 200—6)

1

This invention relates to multiple position switches and more particularly to a switch of the tilting contact plate type.

For many types of applications it is desirable to provide relatively small compact electrical switches selectively to control a plurality of electrical circuits. For example, in aircraft controls it is desirable to provide a single switch mechanism which can control operating circuits in different control elements, such as trim tabs and the like.

Such switches are frequently subjected to rapid operations involving a large number of makes and breaks and often become heated to a relatively high temperature. The switches must therefore be capable of maintaining operation at high temperatures and must be easy to operate under all conditions to provide the necessary sensitivity of control. Furthermore, in the event the contacts should stick the switch mechanism must be capable of exerting enough force thereon to insure separation thereof.

It is one of the objects of the present invention to provide a multiple position switch which satisfies all of these requirements and which is at the same time extremely small and compact.

Another object is to provide a switch of the tilting disc type in which a universal rotatable ball engages and acts on the disc to tilt it.

The use of a ball for this apparatus not only reduces friction and insures smooth and easy operation but also provides a point contact with the disc to minimize transfer of heat to the handle and positively to prevent sticking of the handle to the disc.

A further object is to provide a switch in which the disc is normally urged to its tilted position by a spring pressed plunger and in which the plunger and handle are formed with interengaging parts to limit relative movement thereby to provide a positive mechanical action to break loose sticking contacts.

The above and other objects and features of the invention will be more readily apparent from the following description when read in connection with the accompanying drawing, in which:

Figure 1 is a side elevation of a switch embodying the invention,

Figure 2 is a central vertical section of the switch,

Figure 3 is a horizontal section on the line 3—3 of Figure 2,

Figure 4 is an end view with parts broken away and in section, and

Figures 5, 6, 7 and 8 are transverse sections on

2

the lines 5—5, 6—6, 7—7 and 8—8, respectively, of Figure 2.

The switch as shown comprises a mounting bracket 10 having a flat base portion and an end portion to overlie the end of the switch housing and to form a part thereof. The end portion of the bracket is formed with a central opening defined by outwardly extending curved lips 11 to form a part of a ball and socket joint. The end portion of the bracket is rigidly secured to the end of a cup-shaped housing 12 having a central opening therein defined by curved annular lips 13. Preferably a separating plate 14 is provided between the bracket and the housing and has a central opening therein terminating flush with the socket defined by flanges 11 and 13 except for a narrow projection 15 at one point therein which extends into the socket.

The socket defined by the flanges 11 and 13 receives a spherical enlargement 16 on a tubular handle 17 and supports the handle for universal angular movement. Preferably the spherical enlargement 16 is formed with a slot 18 in which the projection 15 extends to prevent the handle from turning while allowing it to swing angularly in any desired direction.

The handle 17 is normally held in a centered position coaxial with the housing 12 by means of resilient disc 19 formed of rubber or the like, which is supported in the housing between annular plates 21 and 22. The plate 21 is preferably formed with a relatively large circular opening therein through which the handle loosely extends so that the handle can move freely. The plate 22, as best seen in Figure 8, is preferably formed with a series of circumferential projections 23 thereon to fit slidably into slots 24 in the housing 12 so that the angular position of the plate 22 is fixed. In its central part the plate 22 is formed with an opening fitting relatively closely around the handle and having a plurality of lobes projecting radially therefrom in which the handle can move to its various switching positions. In the form shown, four positions are contemplated and the opening in the plate 22 is provided with four lobes 25 spaced 90° from each other. The handle can therefore be tilted to any one of four angular operating positions, and when released will be returned to its centered inoperative position by the resilient disc 19.

The opposite end of the housing 12 is closed by an insulated cover disc 26 which, as best seen in Figure 4, is formed in its periphery with a plurality of spaced notches to receive integral fingers 27 projecting from the ends of the housing. After

the cover disc is inserted against the end of the housing with the fingers 27 extending beyond the disc, the fingers 27 are bent over against the outer surface of the disc to secure it tightly in place.

The cover disc 26 carries a central contact seat 28 which, as shown, is circular in outline with a flat central seating surface and a circular upstanding peripheral flange 29. The contact seat is rigidly secured to the cover disc and carries a connector lug 31 by which it may be connected to a common lead for the several circuits to be controlled. For example, the connector lug 31 might be connected to one side of a source of power, such as a battery. A plurality of fixed contacts 32 are carried by the closure disc 26 and are spaced around the contact seat 28. Each of the fixed contacts 32 carries a connector lug 33 by which it may be connected into any desired circuit such as a circuit controlling motors for operating trim tabs or the like. As shown, four fixed contacts 32 are provided uniformly spaced around the contact seat 28 and registering in position with the lobes 25 of the opening in the disc 22.

The contact seat is adapted to support a tiltable contact disc having a flat circular base portion 34 to seat against the flat surface of the seat within the flange 29. The disc terminates in a peripheral flange 35, which overlies and is normally spaced from the fixed contacts 32, as shown in Figure 2. The opposite surface of the disc is provided with a concave dished cavity 36 which may be arcuate but which is preferably substantially parabolic as shown.

To tilt the disc the tubular handle 17 slidably receives a plunger 37 formed of an insulating material, such as a relatively hard plastic. The plunger is urged outwardly of the handle toward the contact disc by a spring 38 and is adapted to exert pressure on the disc when the handle is tilted to tilt the disc to one of its contact positions as seen in Figure 3.

It has been found that when the end of the plunger, such as the plunger 37, is located to engage the contact disc directly it tends to wear rapidly and, further, tends to soften under the relatively high temperatures which may be developed in operation. Therefore, according to the present invention the plunger 37 carries a metallic cup member 39 which is of slightly larger external diameter than the plunger. A ball 41, such as a conventional steel bearing ball is mounted in the cup member 39 for universal rotation therein and engages the concave surface 36 of the contact disc.

In use, when the handle 17 is released it will center, as shown in Figure 2, to hold the contact disc against the seat 28 in its flat centered position out of engagement with all of the fixed contacts. When the handle is swung to one of its angular operating positions, as shown, for example, in Figure 3, the ball will ride up on the concave surface 36 and will tilt the disc so that the flange portion 35 thereof engages one of the fixed contacts 32. At this time the selected one of the circuits will be completed to effect a selected operation. It will be noted that in its operated position the spring 38 is compressed to a greater extent than when the switch is in its centered position so that the disc will be held against the selected fixed contact with a relatively high pressure. This insures good contact with a minimum of resistance in the circuit and with a minimum chance of arcing. It will also be noted that with this construction a snap action of the disc is produced during both making and break-

ing of the circuit due to the fact that the disc will tilt sharply about its edge in one direction or the other as soon as the line of force exerted by the plunger thereon crosses the edge of the disc base.

With a ball 41 as shown engaging the disc surface the friction between the disc and the plunger is reduced to an absolute minimum in all directions of operation so that the switch can be operated smoothly and easily. Furthermore, because the ball will have substantially a point contact with the disc, transfer of heat from the disc to the handle is minimized so that the handle portion of the switch will not be overheated. Also with a metal ball contacting a metal disc surface the possibility of binding or sticking is eliminated so that the switch will operate properly under all conditions.

In the event a contact should stick tending to hold a circuit closed after the handle is released, the handle can be swung in an opposite direction to exert a breaking force on the contact. Under these conditions the plunger will be moved inward of the handle until the enlarged cup member 39 strikes the end of the handle after which no further movement will be permitted. Therefore as the handle is swung a positive mechanical force will be exerted on the disc to tilt it and this force can be made large enough to break loose a sticking contact without any difficulty. Therefore even if the contacts should stick due to an overload, the switch can still be released by exerting manual pressure on the handle in the direction opposite to that required to close the sticking parts.

While one embodiment of the invention has been shown and described in detail, it will be understood that this is for the purpose of illustration only and is not to be taken as a definition of the scope of the invention, reference being had for this purpose to the appended claims.

What is claimed is:

1. A multi-position switch comprising a housing, a central contact seat carried by one end of the housing, at least three fixed contacts spaced around the contact seat and carried by said one end of the housing, a contact disc having a base portion supported on the contact seat, said disc having a flange portion overlying and normally spaced from the fixed contacts and a concave dished surface facing the other end of the housing, a handle extending through the other end of the housing and supported therein for universal angular movement, a plunger slidably carried by the handle, a spring urging the plunger outward of the handle toward the contact disc, and a ball carried by the outer end of the plunger for universal rotation thereon and engageable with the dished surface of the contact disc to tilt the disc on the contact seat and move the flange portion thereof into engagement with one of the fixed contacts when the handle is swung from a centered position.

2. A multi-position switch comprising a housing, a central contact seat carried by one end of the housing, at least three fixed contacts spaced around the contact seat and carried by said one end of the housing, a contact disc having a base portion supported on the contact seat, said disc having a flange portion overlying and normally spaced from the fixed contacts and a concave dished surface facing the other end of the housing, a handle extending through the other end of the housing and supported therein for universal angular movement, a plunger slid-

ably carried by the handle, a spring urging the plunger outward of the handle toward the contact disc, a ball carried by the outer end of the plunger for universal rotation thereon and engageable with the dished surface of the contact disc to tilt the disc on the contact seat and move the flange portion thereof into engagement with one of the fixed contacts when the handle is swung from a centered position and interengaging parts on the plunger and the handle to limit movement of the plunger inward of the handle whereby a positive pressure can be exerted on the disc to tilt it in the event of contact sticking.

3. A multi-position switch comprising a housing, a central contact seat carried by one end of the housing and formed with a flat seating surface and an upstanding peripheral flange, at least three fixed contacts carried by said one end of the housing spaced around the contact seat, a contact disc having a flat base portion fitting within the peripheral flange and seating against the seating surface, said disc having a flange portion overlying and spaced from the fixed contacts and a concave dished surface facing the other end of the housing, a tubular handle extending through the other end of the housing and supported therein for universal angular movement, a plunger slidable in the handle, a spring in the handle urging the plunger outward thereof toward the contact disc, and a ball mounted on the end of the plunger for universal rotation thereon and engageable with the concave surface of the disc to tilt the disc on the contact seat and move the flange portion thereof into engagement with one of the fixed contacts when the handle is swung from a centered position.

4. A multi-position switch comprising a housing, a central contact seat carried by one end of the housing and formed with a flat seating surface and an upstanding peripheral flange, at least three fixed contacts carried by said one end of the housing spaced around the contact seat, a contact disc having a flat base portion fitting within the peripheral flange and seating against the seating surface, said disc having a flange portion overlying and spaced from the fixed contacts and a concave dished surface facing the other end of the housing, a tubular handle extending through the other end of the housing and supported therein for universal angular movement, a plunger slidable in the handle, a spring in the handle urging the plunger outward thereof toward the contact disc, the plunger being formed of insulating material and of a uniform external diameter to fit slidably in the handle, a metal cup member carried by the outer end of the plunger, and a ball mounted in the cup member for universal rotation therein and engageable with the concave surface of the disc.

5. The construction of claim 4 in which the cup member is of larger diameter than the plunger to seat on the end of the handle and limit movement of the plunger into the handle.

6. A multi-position switch comprising a housing, a central contact seat carried by one end of the housing and formed with a flat seating surface and an upstanding peripheral flange, at least three fixed contacts carried by said one end of the housing spaced around the contact seat, a contact disc having a flat base portion fitting within the peripheral flange and seating against the seating surface, said disc having a flange portion overlying and spaced from the fixed contacts and a concave dished surface facing the other end

of the housing, a tubular handle extending through the other end of the housing and supported therein for universal angular movement, a plunger slidable in the handle, a spring in the handle urging the plunger outward thereof toward the contact disc, a ball mounted on the end of the plunger for universal rotation thereon and engaging the concave surface of the disc to tilt the disc when the handle is swung from a centered position, and a disc of resilient material in the housing fitting over the handle to seal the housing and to urge the handle resiliently to its centered position.

7. A multi-position switch comprising a housing, a central contact seat carried by one end of the housing and formed with a flat seating surface and an upstanding peripheral flange, at least three fixed contacts carried by said one end of the housing spaced around the contact seat, a contact disc having a flat base portion fitting within the peripheral flange and seating against the seating surface, said disc having a flange portion overlying and spaced from the fixed contacts and a concave dished surface facing the other end of the housing, a tubular handle extending through the other end of the housing and supported therein for universal angular movement, a plunger slidable in the handle, a spring in the handle urging the plunger outward thereof toward the contact disc, a ball mounted on the end of the plunger for universal rotation thereon and engaging the concave surface of the disc to tilt the disc when the handle is swung from a centered position, a disc of resilient material in the housing fitting over the handle to seal the housing and to urge the handle resiliently to its centered position, and a rigid disc overlying the resilient disc and formed with an opening through which the handle projects having lobes corresponding in number and angular spacing to the fixed contacts to guide the handle in its tilting movements.

8. A multi-position switch comprising a housing, a central contact seat carried by one end of the housing and formed with a flat seating surface and an upstanding peripheral flange of circular contour, at least three fixed contacts carried by said one end of the housing spaced around the contact seat, a contact disc having a flat base portion of circular contour fitting within the peripheral flange and seating against the seating surface, said disc having a flange portion overlying and spaced from the fixed contacts and a concave dished surface facing the other end of the housing, a tubular handle extending through the other end of the housing and supported therein for universal angular movement, a plunger slidable in the handle, a spring in the handle urging the plunger outward thereof toward the contact disc, and a ball mounted on the end of the plunger for universal rotation thereon and engageable with the concave surface of the disc to tilt the disc on the contact seat and move the flange portion thereof into engagement with one of the fixed contacts when the handle is swung from a centered position.
